UNITED STATES PATENT OFFICE.

PHILIP FREEMAN JACKSON, OF NEW YORK, N. Y.

INDESTRUCTIBLE AND COLLAPSIBLE DRINKING-CUP.

1,116,068.

Specification of Letters Patent.

Patented Nov. 3, 1914.

Application filed November 11, 1913. Serial No. 800,273.

To all whom it may concern:

Be it known that I, PHILIP F. JACKSON, a citizen of the United States, and a resident of the city of New York, Stapleton, borough of Richmond, in the county of Richmond and State of New York, have invented a new and Improved Indestructible and Collapsible Drinking-Cup, of which the following is a full, clear, and exact description.

10 This invention relates to improvements in drinking cups and more particularly to an improved indestructible and collapsible drinking cup.

15 The specific object of the invention is comprehended in the provision of a cup to be pressed or molded of rubber or other resilient material or composition, to lie flat and thereby be rendered especially adaptable to be carried in one's pocket, and also reinforced at its edges to assist in its assumption of a flat position as well as to provide for increasing wearing qualities.

20 With the above and other objects in view, the invention resides more particularly in the peculiar combination and arrangement of parts which will be illustrated as a preferred embodiment in the accompanying drawings and described in the specification.

25 Reference is to be had to the accompanying drawings forming a part of this specification, in which similar characters of reference indicate corresponding parts in all the views, and in which—

30 Figure 1 is a perspective view of one form of my improved indestructible and collapsible drinking cup with reinforced edges; Fig. 35 2 is a vertical sectional view thereof; Fig. 3 is a plan view; Fig. 4 is a plan view of the cup when expanded or open; Fig. 5 is a perspective view of a modified construction in which a reinforcing and expanding wire or 40 spring is employed; Fig. 6 is a vertical sectional view thereof; Fig. 7 is a plan view; and Fig. 8 is also a plan view but showing 45 the cup in an open position.

45 Referring to the drawings and more particularly to Figs. 1 to 4 inclusive, it is here stated that the essential object of the invention is carried out in providing a cup of 50 rubber or other resilient material or composition, pressed or molded into shape and constructed of a single section or piece in such a way that the rubber or composition of which it is made will act to collapse or 55 close the cup automatically but will permit the cup to be crushed without being injured

or carried in one's pocket so that the person will be unaware of its being there and without the noise usually occasioned by the ordinary telescope cup. In said figures the 60 numeral 10 indicates a drinking cup of the material mentioned and which, when in collapsed condition as shown in Figs. 1, 2 and 3, has its side portions 11 disposed closely adjacent so as to lie flat and occupy a minimum space, the general shape being that of a sector of a circle having a round bottom portion 12 and having the free edges 13 convexly arcuate so as to provide edge portions 14 reinforced by a binding 15 in the form of 70 an integral or separate reinforcing strip. By reason of the convexly arcuate edge portions 13, the cup will be caused to form opposite spout portions at the edges 4 when the cup is expanded. This binding extends 75 continuously of the closed edge of the cup and results in an increase in the thickness thereof with increased added resiliency 80 tending to cause the cup to assume a collapsed position as well as to increase the wearing qualities. The rounded bottom also prevents the collection of sediment in the bottom of the cup by insuring its thorough drainage, and by constructing the cup of 85 odorless rubber or some flexible and waterproof material which may be extended, it is obvious that the cup may also be collapsed to occupy a minimum space when being carried and this without injury.

90 In the form of the invention illustrated in Figs. 5 to 8 inclusive, the cup is of similar construction except that in lieu of the binding 15 the edge portion of the cup is reinforced or thickened, as shown at 16, to provide substantially semi-circular projections 95 when the cup is open, as shown in Fig. 8. This rib or edge reinforcing thus provided has mounted therein, either molded or pressed with the cup or inserted after the cup is molded, a wire or other spring 17 100 conforming in shape to the outline of the cup when in collapsed condition, its leg portions being normally spaced apart to exert outward pressure to assist in the collapsing of the cup.

105 In either of the forms of the invention illustrated the cup may be expanded or opened by pressing against the edge portions to cause the same to assume the positions illustrated in Figs. 4 and 8. Owing 110 to the fact that the spring employed in the structure as shown in Figs. 5 to 8, inclusive

is inclosed in the lid or edge reinforcing, contact of the water therewith and consequent rusting or corrosion and resultant contamination of the water or other beverage will be obviated.

Having thus described my invention, what I claim as new and desire to secure by Letters Patent is:—

1. A collapsible drinking cup consisting of a single continuous section of waterproof and flexible material held collapsed and adapted to be expanded by pressure against the top portions thereof when in collapsed condition, and a reinforcing binding continuously of the closed edge portion of the cup to resist the pressure for expanding the cup, said binding being unexposed to the interior surface of the cup, the edges of the cup at the mouth portion being convexly arcuate to cause the same to assume spout portions at the opposite closed edges when the cup is expanded and the bottom of the cup being rounded to prevent the collection of sediment therein.
2. A collapsible drinking cup having opposed flat sides with a narrow connecting edge, the cup flaring toward its mouth portion to produce a substantially truncated member when expanded and opened, and a reinforcing binding around the edge portion

of the cup to strengthen the same and add resiliency to such edge portion to cause the cup to automatically assume a collapsed condition.

3. A collapsible drinking cup having opposed sides with a narrow connecting edge, said cup flaring toward its mouth portion and having a rounded bottom to prevent the collection of sediment therein when the cup is expanded or collapsed, the edge portion of the cup being increased in thickness to provide resilient reinforcements projecting from the exterior face of the cup, and a resilient member of a shape corresponding to that of the cup in side elevation, around which the material is molded at the edge portion to embed the same therein spaced from the inner and outer faces of the cup, said resilient member serving to cause the cup to assume a collapsed condition by outward expansion of its side portions and serving as a reinforcement at the edge portion of the cup.

In testimony whereof I have signed my name to this specification in the presence of two subscribing witnesses.

PHILIP FREEMAN JACKSON.
